DESIGN FOR A DESK

Chester H. Ristenpart, San Francisco, Calif.

Application November 18, 1944, Serial No. 116,428

Term of patent 14 years

(Cl. D33—7)

To all whom it may concern:

Be it known that I, Chester H. Ristenpart, a citizen of the United States of America, residing at the city and county of San Francisco and State of California, have invented a new, original, and ornamental Design for a Desk, of which the following is a specification, reference being had to the accompanying drawings forming part thereof.

Fig. 1 is a perspective view of a desk showing the design.

Fig. 2 is a bottom plan view of the desk shown in Fig. 1.

Fig. 3 is a perspective view showing the rear side of the desk of Fig. 1.

I claim:

The ornamental design for a desk, as shown.
CHESTER H. RISTENPART.
